(57) **CLAIM**

The ornamental design for a digital audio player with tuner and amplifier for an automobile as shown and described.

DESCRIPTION

FIG. 1 is a perspective view of a digital audio player with tuner and amplifier for an automobile showing our new design;

FIG. 2 is a front view thereof;

FIG. 3 is a top view thereof; and,

FIG. 4 is a left side view thereof.

The broken lines shown in the drawings depict portions of the digital audio player with tuner and amplifier for an automobile that form no part of the claimed design.

In FIG. 2, the inverted trapezoid shown at the top is the lighting portion.
